Primary Examiner — W. A. Teddy Falloway(57) CLAIM

The ornamental design for a golf bag, as shown and described.

DESCRIPTION

FIG. 1 is a first perspective view of a golf bag;
 FIG. 2 is a second perspective view thereof;
 FIG. 3 is a first side view thereof;
 FIG. 4 is a second side view thereof;
 FIG. 5 is a front view thereof;
 FIG. 6 is a rear view thereof;
 FIG. 7 is a top view thereof; and,
 FIG. 8 is a bottom view thereof;
 The broken lines show portions of a golf bag that form no part of the claimed design.
